UNITED STATES PATENT OFFICE.

EDWARD E. BERTHOLD, OF CHICAGO, ILLINOIS.

AUTOMATIC REVERSING MECHANISM.

1,366,690.

Specification of Letters Patent. Patented Jan. 25, 1921.

Application filed August 21, 1919. Serial No. 318,904.

To all whom it may concern:

Be it known that I, EDWARD E. BERTHOLD, a citizen of the United States, residing in the city of Chicago, county of Cook, and State of Illinois, have invented certain new and useful Improvements in Automatic Reversing Mechanism, of which the following is a specification.

The invention relates to reversing mechanism for washing or other machines which are actuated by motive power, and it has for its object the provision of reversing mechanism which is automatic in operation, which will positively reverse the direction of movement of the driven element at the proper time, and which is of advantageous construction by reason of its simplicity, compactness and paucity of parts.

The object of the invention thus generally stated together with other and ancillary advantages are obtained by the construction and arrangement illustrated in the accompanying drawings forming part hereof and in which, Figure 1 is a fragmentary front elevation of a preferred form of my improved reversing mechanism applicable to a washing machine. Fig. 2 is a vertical sectional view taken on line 2—2 of Fig. 1. Fig. 3 is a fragmentary detail view of one of the parts of the reversing mechanism. Fig. 4 is a horizontal section taken on line 4—4 of Fig. 2. Fig. 5 is a similar view taken on line 5—5 of Fig. 2.

In the embodiment of the invention illustrated, 1 designates a housing formed upon a supporting bracket 2 and adapted to be closed by a cover plate 3. Within said housing the reversing mechanism is adapted to be inclosed and comprises a drive shaft 4 extending horizontally through the lower portion of the housing and a driven shaft 5 which may form one of the journals of a washing machine drum (not shown). Suitable bearings 6 are provided in the opposite sides of the housing 1 for the drive shaft 4, and a bearing 7 is provided in the rear wall of the housing for the driven shaft 5.

The shaft 5 extends into the housing and has fixed thereon a bevel gear 8 which meshes at all times at diametrically opposite points with two bevel pinions 9 and 9^a rotatably mounted within the housing on the drive shaft 4 but fixed against longitudinal movement thereon. Said pinions are ar-

ranged to be alternately driven from the drive shaft 4 through a shiftable clutch element or sleeve 10 splined upon the shaft 4 by means of a key 11. The clutch sleeve 10 is provided on its opposite ends with clutch faces 12 and 12^a arranged to engage respectively, when the clutch sleeve 10 is properly shifted, with clutch faces 13 and 13^a formed on the hubs of the bevel pinions 9 and 9^a.

The means for shifting the clutch sleeve 10 to alternately connect the pinions 9 and 9^a, whereby to alternately rotate the bevel gear 8 in opposite directions, comprises a lever 14 pivoted at 14^a to the housing 1 upon an upstanding rib 15 (Fig. 2). Said lever is connected a short distance above the lower end with the clutch sleeve 10 in any suitable manner, as by means of an annular groove 10^a in the sleeve, in which the lever is adapted to ride; and near its upper end the lever is connected to a rotary element such as a spur gear 16, which is mounted on a stud shaft 16^a suitably supported by the rear wall of the housing. Said gear 16 meshes with a spur pinion 17 fixed on the driven shaft 5 and is thus directly connected with the driven shaft by which it is given a reciprocatory motion consequent upon the periodical reversal of the clutch. The connection between the lever 14 and the spur gear 16 consists of a tension spring 18, one end of which is fixed to a stud 19 near the periphery of the spur gear and the outer end of which is fixed to a stud 20 projecting forwardly from the upper end of the lever 14. Said spring is constantly under tension, and it will be seen that as the direction of pull thereof changes in the rotation of said gear, the lever is swung by the action of the spring 18 to shift the clutch element 10 from engagement with one of the pinions 9 or 9^a into operative engagement with the other one of said pinions.

For the purpose of controlling the movements of the lever 14 by the spring 18, so that a reversal in the direction of movement of the parts may be prevented until the proper time, or until such time that the spring may exert a positive pull in the direct line of movement of the lever, I provide on the forward face of the spur gear 16 a pair of stop members or projections 21 and 22, and upon the rear face of the lever a pair

of rollers 23 and 24 (Figs. 3 and 4). Said projections are spaced apart a substantial distance to form a groove 25 therebetween (Fig. 2) and the outer edges of said projections are semicircular in form to provide cam surfaces 26 and 27. The rollers 23 and 24 are spaced apart a sufficient distance to permit the passage of the projections therebetween, and are made of such diameter as 10 to be capable of passing freely through the groove when properly aligned therewith. As will be understood, the gearing connections are relatively proportioned so that as the spur gear moves from one position to the 15 other, the driven shaft passes through a predetermined number of revolutions.

In operation, the drive shaft 4, and thereby the clutch element 10 is constantly driven in one direction. In Fig. 1, the clutch element is shown as operatively engaging the pinion 9^a, and in this position of the parts the gear 16, through the bevel gear 8, shaft 5 and pinion 17, is driven in a counterclockwise direction. The shaft 5 continues to operate in its initial direction until the gear 16 moves through substantially a half revolution from the position shown in Fig. 1. In this operation, the cam projection 22 passes between the rollers 23 and 24, with the roller 23 bearing upon the cam face 27 so that movement of the lever 14 is prevented. At the same time, the stud 19, to which the outer end of the spring 18 is connected, moves to a substantially diametrically opposite position, tensioning the spring and changing the direction of its pull; and as soon as the cam projection 22 releases the roller 23 on the lever and the groove 25 becomes aligned with both rollers, the lever 14 is quickly and positively swung to its opposite position.

This movement of the lever carries the clutch element 10 out of engagement with the pinion 9^a and into operative association with the pinion 9. The direction of rotation 45 of the driven shaft 5 is thus immediately reversed, and the spur gear is accordingly rotated in the opposite direction with the cam projection 21 passing between the rollers 23 and 24 and the projection 21 acting to prevent a premature shifting of the lever 14.

It will be seen that I have provided a reversing mechanism of substantial simplicity having a minimum number of parts co-operating to effect positive reversals in the 55 direction of rotation of the driven member at regular intervals. The actuating spring is prevented from acting until it has been placed under maximum tension, and further, until it is in such position as to exert a pull 60 in the direct line of movement of the lever, thus insuring a prompt reversal of the mechanism.

While I have herein described the invention with considerable particularity, it will 65 be understood that in the interpretation of

the appended claims, it is not to be limited except as may be necessitated by the state of the prior art.

I claim as my invention:

1. An automatic reversing mechanism 70 comprising, in combination with a driven element, a reversing clutch, means for actuating said clutch comprising a pivoted lever, a rotary element in continual driving connection with the driven element, and a coiled tension spring having its ends directly attached to said lever and said rotary element respectively whereby in the rotation of said element the direction of pull of the spring is 75 changed. 80

2. An automatic reversing mechanism comprising, in combination with a driven element, a reversing clutch, means for actuating said clutch comprising a pivoted lever, a rotary element having a continually operating gearing connection with the driven element, a spring directly connecting said lever and rotary element and means operatively engaging said lever in the rotation of the rotary element to prevent a premature movement of the lever by said spring. 85 90

3. An automatic reversing mechanism comprising, in combination with an element to be driven, a reversing clutch, a gear element operatively connected with said driven element, a spring directly attached at one end to the gear element and at its other end operatively connected with the clutch and means for controlling the movement of 95 said clutch by said spring. 100

4. An automatic reversing mechanism comprising, in combination with an element to be driven and a reversing clutch, a rotary element continually driven by said driven element, a pivoted lever operatively connected with said clutch, a spring for swinging said lever having one end connected thereto and the other end directly connected with said rotary element, and controlling means for preventing a premature movement of 110 said lever by said spring in the rotation of the rotary element, said controlling means comprising coacting elements on the lever and the rotary element. 115 105

5. An automatic reversing mechanism comprising, in combination with an element to be driven, a reversing clutch, a lever connected with said clutch to move it, a rotary element continually driven by said driven element, a spring directly connecting said lever with said rotary element and adapted to be tensioned in the rotation of said element to swing the lever, and means adapted to operatively engage with the lever to control the movements thereof. 120 125

6. An automatic reversing mechanism comprising, in combination with an element to be driven, a clutch, a lever for moving the clutch, and means for swinging the lever comprising a spring, means for tensioning 130

the spring and changing the direction of pull thereof including a rotatable element geared directly to the driven element, and means for controlling the movement of said lever 5 comprising a pair of cam devices on said rotatable element operatively engaging with said lever.

7. An automatic reversing mechanism comprising, in combination with a driven 10 element, a reversing clutch, a shifting lever for the clutch, means operable to swing said lever including a tension spring, and an element to which said spring is directly attached geared directly to the driven element 15 and operable to change the direction of pull of said spring.

8. An automatic reversing mechanism comprising, in combination with an element 20 to be driven, a rotatable element having a continually operating gearing connection

with said driven element, a reversing clutch, spring means acting directly between said rotatable element and said clutch to shift the latter in the rotation of said element, and co-operating devices on said lever and rotatable 25 element for controlling the movement of the lever.

9. An automatic reversing mechanism comprising, in combination with a driven element, a reversing clutch, a reciprocating 30 member actuated in continual operation by said driven element, and means operable to periodically reverse said clutch, said means including a spring directly attached to said member and operatively connected to said 35 clutch.

In testimony whereof, I have hereunto set my hand.

EDWARD E. BERTHOLD.
